UNITED STATES PATENT OFFICE.

GEORGE E. MARLATT, OF PASADENA, CALIFORNIA.

LINOTYPE-MACHINE.

1,310,488.

Specification of Letters Patent. Patented July 22, 1919.

Application filed September 21, 1915. Serial No. 52,956.

To all whom it may concern:

Be it known that I, GEORGE E. MARLATT, a citizen of the United States, residing at Pasadena, in the county of Los Angeles and 5 State of California, have invented a new and useful Improvement in Linotype-Machines, of which the following is a specification.

My invention relates to type casting means for typographical composing machines and 10 particularly to the molds of such machines, and has for its object the provision of a plurality of adjustable molds arranged on the face of the mold disk in such a manner that they may be used one after the other in regular 15 succession and having a range of adjustment for the length of the slugs produced.

The applicant is aware that various patents have issued for line casting molds of the universal kind, but believes these inventions 20 have proved impracticable in their application to linotype mold carriers of the established dimensions and associated requirements, such, for instance, as non-interference with the mold disk turning pinion, locking 25 bushings and studs, the matrix holding yoke, and with each other were an attendant made to employ such molds on the same mold disk. In several of said patents, and especially in those which are truly universally adjustable, 30 the mechanism surrounding the mold slot is of such a character that it would not be effectively operable on the common form of linotype mold carrier, chiefly for the reason that in length the entire mold is of necessity 35 so much longer than the mold slot.

In common practice, the molds are positioned close to the edge of the mold carrier and the maximum length measurement of the casting slot is in most instances more 40 than one-third and in some instances more than two-fifths the entire diameter of the disk. As a matter of fact several of such 45 patents are not intended to be applicable in connection with the usual linotype method of ejecting the slug facewise from the mold or in connection with the usual form of linotype matrix. In certain of said patents the parts inclosing the mold slot and forming the mold inner walls are spring pressed, one 50 against the other, and practice has shown that with such devices films of type metal enter and accumulate between the parts, increasing the thickness of the slug, and therefore preventing the passage of the slug between the usual trimming knives in the ejection 55 of the slug from the mold.

In others of said patents, while the molds are universally adjustable for thickness and length of slug, the manner of adjusting the same is such that nothing is gained in time 60 over the customary method of substituting one for another liner of various length and thickness. This is because screws are employed for loosening, tightening and adjusting the several parts of these inventions. 65 The purpose of the invention herein disclosed is to provide a universally adjustable mold devoid of the objections enumerated above and the claims forming a part of this application are accordingly drawn. 70

A further object is the provision of means in the mold for confining the matrices in a line at several different levels in the mold during the casting operation, for adapting the mold for use with specially constructed 75 matrices having full-length and half length ears and several character cavities on both sides thereof of varying dimensions.

Referring to the drawings, in which similar characters of reference indicate the same 80 parts throughout the several views, Figure 1 is a front elevation of the mold disk with my adjustable molds arranged thereon; Fig. 2 is a plan of Fig. 1; Fig. 3 is a sectional elevation of the same on the line 3—3; Fig. 85 4 is a fragmentary sectional elevation of the same on the line 4—4; Fig. 5 is a section of the same on the line 5—5; Fig. 6 is an enlarged front view of the mold sectors and some of the related parts; Fig. 7 is an enlarged perspective view of the mold adjusting 90 block; Fig. 8 is a full size front elevation of the mold adjusting block in operative position in the mold; Fig. 9 is a fragmentary elevation of one of the molds; Fig. 10 is a sectional plan of the mold sectors and plates; Fig. 11 is a front elevation of the mold with my improved reversible face plate shown 95 thereon; Fig. 12 is a sectional elevation of the same on the line 12—12; Figs. 13, 14 and 15 are similar sections on the lines 13—13, 14—14 and 15—15, respectively of Fig. 11; Fig. 16 is a left hand end elevation of the first elevator jaw showing a spaceband confined between the depressible plates; Fig. 17 100 105 is a side elevation and Fig. 18 is a sectional plan of Fig. 15.

The means disclosed provides a combination of molds readily adjustable and capable of producing any length or thickness of slug 110 without the use of liners.

The mold disk 1 is mounted on the pin or

shaft 3 and the pinion 2 is mounted on the shaft 4 in any suitable manner. In the form shown four molds are provided which are suitably carried on the face of the mold disk 1, three of the molds, 5, 6 and 7 being of the improved type as this number is necessary to provide the desired range of adjustment for the length of the slugs produced and the other mold 8 being of the commonly used type and sufficiently shortened to provide space for an individual type mold, if such is desired, and all of the molds occupying positions on the four quarters of the mold disk.

15 The molds 5, 6 and 7 are secured to the disk 1 in the usual manner by screws 10 and are selectively and individually adjustable as to the length of the slugs but are equally adjustable as to the thickness thereof. The 20 adjustment longitudinally of the mold is accomplished by means of a cubical block 11 which is provided with a plurality of rectangular teeth 12 on all of its six sides, the pitch of the teeth being the same on all sides and 25 all of the teeth having the central grooves 13 extending across the entire width of the block for purposes which will appear as the description proceeds.

The pitch of the teeth 12 on the block 11 30 is preferably one half em of type measurement and the teeth on each side of the block are numbered in subdivisions of a half em, as at "6", "3", etc., these numbers indicating points or units of measurement. Thus 6 35 would represent one-half em, 4 one-third em, 3 one-fourth em, 2 one-sixth em, etc. Any one of these numbered surfaces may be selected for establishing the length of the mold slot for ems or half ems and fractions there- 40 of, as desired. The molds 5 are provided with a suitable rack 14 formed on the matrix holding portion 15 which is movable end- wise, and the teeth on the rack engage those on the block 11. The fixed and stationary 45 portion of the mold has a suitable recess 16 in which the block 11 seats and the bottom of the recess has a bore 17 and a counterbore 18 in which a plunger 19 is seated, the plunger carrying a spring 20 and having a head 21 with a rib 22 on the top for engaging and locking the block 11 in position. The spring 20 compresses against the head 21 of the plunger and serves to normally maintain the engagement of the rib 22 with the teeth on 55 the block 11.

The block 11 is movable downwardly in the recess 16 against the tension of the spring 20 in order to disengage the teeth on its upper side from the rack 14 to permit the 60 longitudinal adjustment of the movable part 15 of the mold, which may then be set to a suitable scale provided on the face of the mold.

For unusual adjustments in subdivisions 65 of half ems, the plunger 19 being depressed,

when the block 11 is disengaged from the rack 14, the plunger may be held down by means of a suitable instrument inserted in a groove 23 formed in the lower end of plunger 19 while the block 11 is removed from the recess 16 and turned so as to present another of its sides for engagement with the rack.

As an end closing means for the casting slot of the mold 1 provide a member 24 75 which is adjustably secured to the movable portion 15 of the mold by means of a screw 25, and this member has an end 26 which extends outwardly to a point flush with the face of the mold and a flat arm 27 which is 80 slightly less than the thickness of the disk 1. The member 27 is movable in the slot 28 in the disk 1 when the portion 15 is moved, and is of sufficient length to cover the pot mouth-piece 9 regardless of the length of the casting slot 29. An opening 30 is provided in the opposite side of the disk 1 which registers with the opening 28 and permits the movement of the portion 15, as described.

The mold cap 33 has parallel slots 31 90 through which screws 32 carried by the mold disk 1 extend, for permitting the vertical adjustment of the cap thereon. The cap is rigidly connected with the cross plate 34 by means of vertical members 35, one of which 95 members is guided by means of its engagement with a suitable slot in the mold base and the other member in a guide block 36 secured to disk face by screws 37 and the dowel pins 38 at the end of the mold.

The cap 33 and the plate 34 are movable vertically by means of sectors 39 and 40 which are pivoted, respectively, in a recess 41 in the mold 8 on a screw 42, and on a screw 43 on the disk 1. Each of the adjustable molds has a pair of these sectors which are provided on their inner ends with intermeshing teeth, so that when the sectors are raised by hand the plate 34 will also be raised by means of the pin 44 secured in the 110 plate 34 and adapted to engage the slots 45 in the sectors.

Interposed between the plate 34 and the disk 1 and slidably held on the former, is a flat spring 46 having on one end an up- turned portion 47 projecting through the opening 47' in the plate 34 and having a pin 49 engaging a slot 50 in the plate. The end of the pin 49 is extended upwardly through the opening 51 in the sector 39 to permit the 120 lateral movement of the spring. When pressure is exerted on the pin 49, the end 47 of the spring 46 is thus disengaged from the slot 47', so that the spring may be moved longitudinally for the purpose hereinafter 125 set forth. The pin 49 serves to both disengage and to move the spring and the member 46 functions as a spring only for the purpose of permitting its end 47 to be disengaged from the slot 47'.

The sectors 39 and 40 are also provided with radial slots 52 having teeth on the two curved sides which engage the toothed blocks 53 carried by the spring 46, and the blocks 5 are cross connected on the outer sides of the sectors by means of a member 54 which is secured to the blocks by means of screws 55.

The end 47 of the spring 46 engages the opening 47' for the purpose of holding the 10 blocks 53 to the left of the openings 52 for locking the sectors when setting the mold cap to graduations in full points, and it engages the opening 50 for holding the blocks to the right for graduations in half points.

15 The pin 49 serves to disengage the spring end 47 from the slot 47'. The slideable portion 15 of the mold has a downwardly extending member 56 and this extension has tongues 57 formed on opposite sides which 20 slidably engage the grooves 58 in the mold base and in the face of the disk 1.

While the foregoing description of the mold parts is illustrated in only a single one of the molds shown in Fig. 1, the same parts 25 are used in the other molds and the parts are to all intents and purposes the same though the exact dimensions and form of the molds and mold parts may be somewhat altered in the several molds for convenience 30 in location, as for instance, the space bar 60 which is secured at its upper end to the movable portion 15 of the mold, is shown in Fig. 1 in the upper mold 5 as being straight, while in the right hand mold 6, it 35 is shown curved in the center to avoid contact with the pin 61. This bar 60 engages the upper edge of the plate 34 at its lower end in order to hold the parts 24 in contact with the mold cap 33, and is movable in a 40 slot 66 formed between the base A of the mold and the face of the mold disk 1. The slot through which the screw 25 enters to join the member 24 to the end of the member 15 permits the lateral movement of member 24 when the sectors are moved. 45

In Fig. 1 the end closing means 24 of the upper mold 5 is shown in position at the extreme limit of its movement to the left; in the right hand mold 6 it is shown in position 50 in the center of its movement; and in the lower mold 7 it is shown in position at the limit of its movement to the right.

As a means for closing the right hand end of the mold I provide a closing member 55 62 which is secured to the mold disk 1 at the end of the casting slot by means of a screw 63 and the dowel pin 64. This member has a projecting flange 65 which serves as a 60 guide for the mold cap 33, the cap being narrowed at the end so that it may occupy the space between the flange 65 and mold disk face, and it also serves to hold the cap 33 in close contact with the member 62.

I provide means for drawing the ribs on 65 the slugs and thus forming the upper edge

thereof parallel with the bottom edge regardless of the operation of the trimming knives. This means consists of a plurality of rib cells 33' in the bottom of the mold cap 33, the floor of the cells being inclined 70 from the front toward the rear of the mold and the extreme ends of the cells being closed, as shown in Fig. 3. The slug body between the ribs is usually narrower at the back than at the front, whereas the ribs on 75 the slugs previous to their ejection from the mold are the reverse. In the present invention the ejection of the slugs from the mold serves to draw out the ribs parallel with the opposite side of the slug.

80 As the slug is ejected, the ribs, by contact with the lip of the mold cap, are spread and drawn so as to accommodate the thickness permitted by the measurement of the mouth of the mold. As the thinner part of the slug body approaches the wider front edge of the mold cell, space is provided between the slug and the mold cap, and the slight excess of material on the rib is spread into the space thus provided. Practice has shown that 90 part of the material is drawn out at the rear end of the rib and for this reason the rear end of the rib cell is closed, producing a rib slightly shorter than the slug width, so that when the slug is ejected, the excess material 95 in the rib will not extend beyond the foot of the slug. It should be understood that the roots of the rib cells are almost parallel with the floor of the mold cell, the additional depth of the cell near the foot of the slug 100 being mostly the result of the taper on the slug body. The chief purpose in thus having the slugs leave the mold with parallel sides is so that the ribbed side of the slug need not come into contact with the usual trimming knife in case a large initial letter or figure overhangs the face of the slug. In such case the knives are opened and spaced apart so as to permit the passage of the overhanging character.

110 The operation of the adjustable molds and the delivery of the metal from the pot mouthpiece is accomplished in the ordinary manner in so far as the actual casting operation is concerned; the arrangement on the mold disk is such that a maximum efficiency in the operation thereof may be had, and the entire mechanism insures great economy in the operation of the machine. It should be understood that all contacting surfaces 115 on the molds may be recessed, if necessary or desirable, to provide for the accumulation of dirt and scale thereon.

In Figs. 11 to 15 inclusive, is shown 125 means for confining a line of matrices at different levels in front of the mold, which consists in the improvements in the mold and the first elevator casting jaw, which I will now describe. This form of mold includes a face plate 70 which has a plurality 130

of parallel longitudinal grooves 71 for receiving the matrix ears of either the full length or half length type, and the plate is reversible on the mold in order to accommodate either type of matrices. These grooves receive the matrices at a maximum of four different levels, depending upon the distance to which the casting jaw may be lowered, and receive the matrix ears at 10 three different levels in mixed relation.

The face plate 70 may be made in several forms in so far as the grooves 71 are concerned, and any one of the several forms of plates may be substituted for another in the 15 mold in order to accommodate a selected type of matrix. The mold is so constructed that only those of the screws 72 which serve to hold the face plate thereon are necessarily removed for the purpose of releasing the 20 face plate and reversing it on the mold. The heads 73 of the screws 74 which hold the mold base 75 and the mold carrier 75' together, extend entirely through the face plate, are secured in the mold base and their 25 appearance on the face of the mold merely indicates a clearance in the face plate for the screw heads.

It should be noted that all of the screws appearing on the face of the mold are on a 30 common line with the locking bushing 76 which is common to all line casting machine molds, and also that the sets of screws on either side of the center of the bushing 76 are positioned equidistant therefrom in order to permit the reversal of the face plate around the bushing as its axis.

In Fig. 11 the face plate 70 is shown broken at one end in order to show the opposite ends thereof in reversed positions on 40 the mold. The face plate has a longitudinal rib 77 on its lower edge for increasing the thickness of the lower lip 78 of the mold when matrices of the form shown in Fig. 12 are in use. In this view a modified form of 45 filling piece 79 is shown which is intended to be used in lieu of the rib 77 and which is clamped in position on the mold by means of its beveled edges 80 which engage similar edges of the adjacent face plate of the modified form.

In Fig. 11, it will be observed that the ribs 81 and 82 are in different positions on the face plate relative to the center thereof, and when the plate is reversed, the distance 55 between the upper or operating rib and the mold slot 83 is increased or diminished for the purpose of registering the character cavity of a selected form of matrix with the mold slot. Other modifications of the face 60 plate are shown in Figs. 13 and 14, the grooves on one side of the center in Fig. 13 being three in number for accommodating three letter matrices while the grooves on the opposite side of the center are four in 65 number for accommodating four letter mat-

trices. In Figs. 14 and 15 the casting jaw is shown in its lowest position, in front of the mold; in Fig. 13 in its highest position; and in Fig. 12 in a central position.

By limiting the descent of the casting jaw 70 84 to lower or higher positions, as shown, lower and higher character cavities on the multiple letter matrices may be presented to the mold. As for instance, the lowering of the four letter matrix to a central position 75 in front of the casting jaw will cause the second character thereon to be presented to the mold slot, and by lowering the jaw to its lowest position, the third character may be presented. In order to present the fourth 80 character to the mold, the matrix should be assembled at a level in the assembling elevator which will permit its transfer to a position on an upper rib 85 on the multiple rail 86, and this rib is also used when matrices are mixed at three levels, in which 85 case the casting jaw would be lowered to either the central or lowest position, depending upon and as determined by the character selected for use. 90

The rail 86, as shown in Fig. 13, which has the ribs 85 and 87 is intended for use only in connection with four letter matrices and may be readily substituted for a rail having but one rib and adaptable to all forms 95 of matrices. Another form of rail 88 is shown in Fig. 12 which is easily reversible on the casting jaw for the purpose of placing the rib 89 thereon at an upper or lower level. The ribs to be used for matrices having full length lower ears must occupy positions at an upper level, as shown in Figs. 14 and 15, while those used with matrices having half length ears must occupy positions 100 at lower levels, as shown. 105

The rail of either form represented by 86 or 88 is mounted between the body 90 of the casting jaw and the plate 91 which is secured to the jaw near opposite ends by screws 92, a clearance opening 93 being provided in 110 the rail through which the screws extend. The rail is held resiliently in position by means of springs 94 seated in recesses 95, as shown in Figs. 13 and 18, which compress against the ends 96 of the recesses in 115 the rear wall 97 of the yoke member 98 on the bottom of the jaw. Operating levers 99 carried by the jaw are for the purpose of moving the rails from the matrix channel into the jaw, the levers 99 having depending 120 arms 100 which engage diagonal cam slots 101 in the rails near opposite ends. The action of the arms 100 against one side of the diagonal cam slots causes the ledge 86 to be retracted. There is a clearance between the arms 100 and the inner edges of 125 the diagonal slots to permit the reverse movement of the arms prior to the restoration of the ledge by the springs, since this restoration can not occur until the yoke has 130

been depressed by the combined tension of the springs 107 and 103, thus disengaging the yoke from lugs on the rail, whereupon the yoke is raised by means of the springs 5 111. These levers have spurs 102 to which opposite ends of a longitudinal spring 103 are secured and their outer ends 104 carry pins 105 which extend into the jaw while the opposite ends 106 thereof rest upon the 10 upper edge of the rear wall 97 of the yoke member 98. Springs 107 are carried in suitable recesses 108 in the jaw and the lower ends are secured to the inner ends of the lever pins 105 while the upper ends are 15 secured to pins 109 secured in the outer wall of the jaw. The front wall 110 of the yoke serves as a rail for supporting the matrices at their lower level in the jaw and for raising all of the matrices to an extreme 20 common upper level for effecting their transfer to the second elevator, the raising of the matrices occurring subsequent to the withdrawal of the rail 86 from the matrix channel. The raising of the yoke 98 is effected 25 by means of springs 111 which are secured thereto by means of pins 112 near opposite ends, and the upper ends of the springs being secured to pins or screws 113 in the jaw. The upward movement of the yoke while 30 the rails have been extended and until their entire withdrawal is prevented by means of extensions 114 on the rails 86 and 88 which engage the upper sides of the shoulders 115 on the rear wall of the yoke.

35 The yoke is depressible by means of the inner arms 106 of the levers 99 which frictionally engage the upper edge of the yoke, as described, the combined tension of the springs 107 exceeds that of the springs 111, and the pins 105 on the levers 99 move vertically in slots 116 in the jaw which communicate with the recesses 108. The inner ends of the pins 105 are secured to and support a vertically movable plate 117 which 40 operates in a recess 118 in the mold side of the jaw, and the movement of this plate effects the operation of the levers 99 for releasing or depressing the yoke 98.

45 Pins 119 are carried by the upper end of the plate 117 and are movable through and in the jaw plate 120 which is held on the jaw by means of screws 121. The pins 119 are depressed by means of a suitable and well known member connected with the transfer mechanism with which they engage when the elevator reaches its uppermost or transfer position. The operation of the yoke 98 by the depression of the pins 119 and the movement of the plate 117 will raise 50 the matrices in the line to a common level in readiness for their transfer to the second elevator. Vertical guide pins 122 are provided in the recesses 108 for holding the yoke 98 in the proper position and the lowermost position of the yoke is established by

the pins 123 which are secured to the casting jaw and move in slots 124 in the yoke.

55 The spacebands 125, as shown in Fig. 16 are held in the oppositely formed grooves 126 in the front wall 127 of the plunger plate 117 of the casting jaw by their ears 128. The front wall and plunger plate are secured to a spacing block 129 by screws 130 and 131 and the three members thus form a solid yoke which is depressible by the pins 119 75 and which is withdrawn by means of springs 107 and 103, as previously described. The relative positions of the matrices 132 and the spacebands 125 is such that the spacebands are supported in laterally opposite 80 grooves in the channel walls in the usual manner. The improvements just described and which pertain to the first elevator jaw and the mold are fully described in connection with other improvements of my invention which are included in an application filed by me on September 21st, 1915, Serial No. 52953, and to which reference is had for a full disclosure of the entire matrix 85 mixing means.

90 Having thus described my invention, what I claim is:—

1. In a linotype machine, the combination with a mold disk, of a mold base; a mold cap; co-acting sector means connected with 95 and adapted to laterally adjust the position of said cap on said mold for regulating the width of the casting slot therein; an intermediate portion slidable lengthwise on said base and forming one side of said slot; a 100 rack on the lower side thereof; a cubical block seated in said base and having a plurality of teeth on each side thereof adapted to engage said rack for adjusting the longitudinal position of said intermediate portion and thereby regulating the length of said slot; and means for resiliently holding said block in engagement with said rack.

105 2. In a linotype machine, the combination with a mold disk, of a mold base; a mold cap; a pair of oppositely mounted co-acting sectors pivoted to said disk; means for connecting said sectors with said cap; means for locking said sectors and said cap in a desired position; an intermediate portion in said 110 mold slidable on said base and forming one side of the casting slot therein; a rack on the lower side thereof; a cubical block seated in said base having a plurality of teeth on each side, the teeth on each of the sides 115 being in varying relation to the center of said block and adapted to engage the teeth in said rack for regulating the length of said slot; and means for resiliently holding said block in engagement with said rack.

120 3. In a linotype machine, the combination with a mold disk, of a mold base; a mold cap; a pair of oppositely mounted co-acting sectors pivoted to said disk; means for connecting said sectors with said cap; a radial 125

130

- slot near the inner end of each sector having a plurality of notches on the curved sides thereof; pawl means for engaging said notches for locking said cap; an intermediate portion in said mold adapted to slide on said base and forming one side of the casting slot therein; a rack on the lower side thereof; a cubical block in said base having a plurality of teeth on each side in 10 varying relation to the center of said block and adapted to engage said rack; and a plunger resiliently seated in said base below said block having a rib on its head adapted to engage said block for holding 15 said block in contact with said rack.
4. In a linotype machine, a mold for confining the matrices during the casting operation and having a face plate provided with matrix engaging ribs on the upper and lower 20 portions thereof and reversibly held thereon for adapting the mold for the holding of matrices at different levels therein.
5. In a linotype machine, a mold for holding the matrices during the casting operation and having means for holding the 25 matrices at different levels, said means having ribs on each side of the center for engaging the matrices, and means insertible therein for adapting the mold for use with 30 matrices of unusual character when said matrices are held at their highest level therein.
6. In a linotype machine, a mold having means for holding matrices at different 35 levels therein and a face plate therefor having matrix confining ribs on opposite sides of the center and reversible, at will, for rendering any of the ribs operative.
7. A mold for typographical machines 40 having means for receiving and holding matrices having both full length and half length ears, and a reversible face plate carried thereby having ribs formed thereon at top and bottom capable of being selectively 45 positioned with respect to the mold for operation.
8. In a linotype machine, a slug casting mold having a mold slot with two opposed inclosing walls, one of said walls having 50 formed therein transverse rib cells, said cells being deeper at their rear or intake end than at their front or ejecting end, relative to said other inclosing wall.
9. In a linotype machine, a mold, a fixed 55 mold base having matrix alining grooves formed therein, a mold side wall manually adjustable longitudinally in said base, a mold end wall carried by said side wall and adjustable transversely thereof, and a multi-faced notched block held in said base for 60 locking said side wall and said end wall in

adjusted positions, the notches on the sides of said block bearing different relations to the center of the block and arranged in subdivisions of half ems of type measurement, 65 for the purpose of correspondingly positioning said mold walls.

10. In a linotype machine, the combination of a mold carrying disk limited in diameter to less than two and one half times 70 the measurement of the maximum length adjustment of the molds carried thereby, a two-way adjustable linerless mold structurally limited as to its minimum and maximum length adjustment by the diameter of said 75 disk, a second two-way adjustable linerless mold having a minimum length adjustment approximating the minimum length adjustment of said first mold and having a corresponding range of adjustment, and a third 80 two-way adjustable linerless mold having an adjustment relative to said second mold and similar to the relation between said first and second molds, said molds being 85 equally adjustable transversely of their length.

11. In a linotype machine, the combination of the laterally adjustable mold cap 33, connected by means of guide bars 35 to a longitudinal bar 34 underlying the mold; 90 inter-meshing sectors 39 and 40 connected with said longitudinal bar for laterally adjusting said mold cap, and means for locking said sectors in order to maintain any desired adjustment of said mold cap; the longitudinally adjustable member 15 forming the floor of the mold slot and carrying the end wall 26 thereof, said end wall being confined between the mold cap 33 and bar 34 for lateral movement therewith and in contact with the mold cap regardless of its longitudinal movement with member 15; a follower 27 carried by said end wall for sealing the portion of the mold carrier vacated by end closing wall 26; a notched rack 105 14 integral with member 15, and a multi-faced locking block 11 arranged for engagement and disengagement relative to said rack, for locking said member 15 against displacement and for releasing the same for 110 adjustment, respectively; and an opposed end closing wall 62 for the mold slot, said wall 62 being fixed to said mold carrier and serving as a guide and coöperating keeper for mold cap 33.

Signed at Los Angeles, in the county of Los Angeles and State of California this 23d day of August, 1915.

GEORGE E. MARLATT.
In the presence of:

CHARLES H. WILD,
J. D. HASKIN.
